UNITED STATES PATENT OFFICE.

JOHN N. DART, OF RICHMOND, VIRGINIA.

PIPE-SHIELD.

1,399,851.

Specification of Letters Patent. Patented Dec. 13, 1921.

Application filed April 8, 1921. Serial No. 459,528.

To all whom it may concern:

Be it known that I, JOHN N. DART, a citizen of the United States, and resident of Richmond, in the county of Henrico and State of Virginia, have invented certain new and useful Improvements in Pipe-Shields, of which the following is a specification.

My invention relates to tobacco pipes, and is directed to an improved shield for the mouth of the pipe bowl.

A principal object of my invention is to provide a shield which will protect the pipe from the effects of wind, thereby adapting it for use out of doors, and especially by automobilists. In the preferred form the tobacco will also be protected against rain.

A further object is to provide a pipe which will facilitate even and rapid combustion of the tobacco without sacrificing adequate protection from the elements.

Furthermore, I have provided a shield so constructed that the pipe may be lighted when the shield is closed, and if desired the shield may be so proportioned that it will provide protection for the match from wind and rain.

A further object is to provide a shield that will permit prompt and free access to substantially the entire bowl of the pipe at any time without diminishing the protective effect of the shield.

Another object is to provide an efficient shield without employing the unsightly and cumbersome structures heretofore used. A pipe equipped with a shield embodying my invention is not only neat and attractive in appearance, but is sufficiently compact to permit it to be carried in the pocket or even placed in an ordinary case without difficulty.

In the preferred construction shown, I also attain an object which is important from the commercial point of view, as the type of shield disclosed is readily constructed from a single sheet of metal by a very simple process; and whether constructed from a single sheet or from two or more parts rigidly connected to each other, the shield is so simple and strong that it will withstand long and hard usage.

Other objects and advantages of my invention will be apparent from the following description, taken in connection with the accompanying drawings, in which;

Figure 1 is a perspective view of a pipe with the shield closed, 55

Fig. 2 is a fragmentary vertical section through a portion of the pipe bowl and shield, the open position of the shield being indicated in dotted lines, and

Fig. 3 is a plan view of the shield and 60 mounting.

Upon the pipe bowl 10 is mounted the shield or cover embodying my invention, which includes a body 11 preferably slightly convex and having an outer edge extending 65 along substantially the entire upper edge of the pipe bowl. Centrally of the body 11 there is formed or mounted a concave hood 12 having a laterally directed opening 13 communicating with the inside of the pipe 70 bowl. The hood may obviously vary considerably in size and shape, the general object being to so proportion the hood that a free passage of substantial area throughout will be provided between the bowl of the pipe 75 and the outer air. The proportions illustrated have been found suitable, and it will be noted that in this type the margin of the hood 12 is located entirely within body 11, though the hood and body together cover 80 substantially the entire top of the pipe.

I have also found that by providing a draft substantially from the center of the pipe the tobacco will burn more readily and evenly, so that the employment of a shield 85 does not substantially interfere with smoking. This object has been accomplished by locating the opening 13 fairly near the center of the pipe, and shaping the hood 12 so that the draft through opening 13 will be 90 approximately central. By suitably shaping the top of hood 12 to give it a slope downwardly to the left as shown in Fig. 2, the opening 13 may be located somewhat to the right of the center in order to provide ample draft at the right point. This arrangement furthermore permits an opening of the maximum size without weakening the body 11 of the shield. This feature has a further advantage in permitting the user to light 100 the pipe readily while the shield is closed, as a match may be inserted through the opening, or the flame sucked into it and over a considerable area of the tobacco.

The front edge 14 of hood 12 adjacent 105 the opening 13 is preferably close to vertical

- alinement with the adjacent edge 15 of the shield body, to prevent the entrance of any substantial amount of rain through the opening when the shield is closed. In the 5 form shown edge 14 of the hood is inclined slightly; but this is not essential as the edges of opening 13 can be located to provide any amount of protection against the entrance of rain through the opening.
- 10 I preferably form hood 12 integral with body 11, and they may both be formed from a single sheet of metal by means of simple dies. However, it is apparent that this construction, while highly convenient, may be 15 varied without departure from the invention.
- The shield may be mounted on the pipe bowl in various ways, but it is important that it be readily removable to provide access 20 to the entire bowl. For this purpose it is convenient to employ a ferrule 15^a mounted about the upper edge of the pipe and connected by hinge 16 to the shield. At the opposite side of the shield from the 25 hinge I may employ a latch 14 of any type, the one illustrated having a latch tongue 18 engaging a suitable projection 19 on the ferrule 15^a, and provided with an out-turned lower tip 20 which forms a finger piece for 30 releasing the latch and throwing back the cover. It has been found convenient, especially when the pipe is used by automobilists, to have the hood 12 directed rearwardly, and to arrange the hinge and latch so that 35 the cover will swing up away from the smoker; but these features may obviously be varied, both as to the direction of the hood and the location of the hinge and latch elements.
- 40 When the smoker desires to fill his pipe, the shield may be thrown backward on hinge 16 into position shown in dotted lines in Fig. 2, giving as complete access to the bowl of the pipe as is obtained where no shield 45 is used. After filling, the pipe may be lighted with the shield in this position, or if wind or rain makes this inadvisable, the pipe may be lighted either with the shield slightly elevated to form a guard against 50 the wind, or with the shield entirely down, as above noted. Hood 12 will divert wind blowing across the pipe away from the opening 13, even though the wind should be blowing across the pipe instead of directly 55 in the face of the user; and when the wind is at the back of the user his head will afford adequate protection. As a matter of fact, the dead air spaces in the pipe prevent serious disturbance even if the wind 60 should blow in such a direction as to enter the opening 13. Moreover, the hood is shaped so that a wind will not produce undue draft on the pipe, though it does not interfere with smoking, this object being attained 65 by the stream line curves of the hood

which cause the least disturbance in air passing over it.

I am aware that numerous other shields for pipes have heretofore been employed, some of which embody certain of the objects heretofore indicated; but none of the shields heretofore known accomplishes all the objects in a single construction, and certain features of my invention are believed to be absolutely novel in and of themselves. 75

While I have shown and described a preferred embodiment of my invention and indicated certain variations, it will be apparent that numerous other changes may be made by one skilled in the art within the 80 scope of my invention as set forth in the following claims.

I claim:

1. A pipe shield adapted to cover substantially the entire bowl of the pipe, and 85 including an inclined hood terminating at a draft opening spaced throughout from the edges of the shield and bowl.

2. A pipe shield adapted to cover substantially the entire bowl of the pipe, and 90 including an inclined hood terminating at a draft opening adjacent the center of the bowl spaced throughout from the edges of the shield and bowl.

3. A pipe shield including a hood portion 95 terminating in a substantially vertical draft opening, and a marginal portion entirely surrounding said hood portion and opening and overlying the top of the bowl.

4. A pipe shield including a hood portion 100 formed of sheet material and terminating in a substantially vertical draft opening, and a marginal portion of sheet material rigidly connected to the hood portion, entirely surrounding said hood portion and opening, and 105 overlying the top of the bowl.

5. A pipe shield including a hood portion terminating in a substantially vertical draft opening, and a marginal portion entirely 110 surrounding said hood portion and opening and overlying the top of the bowl, said hood and marginal portions being formed from a single sheet of metal.

6. A pipe shield including a hood portion terminating in a substantially vertical draft 115 opening, and a marginal portion entirely surrounding said hood portion and opening and overlying the top of the bowl, and means for connecting the shield to a pipe adapted to permit the shield to be shifted entirely 120 clear of the pipe bowl mouth.

7. A pipe shield including a hood portion terminating in a substantially vertical draft opening, and a marginal portion entirely 125 surrounding said hood portion and opening and overlying the top of the bowl, a support adapted to be connected to the pipe bowl, and a hinge connection between said support and shield, whereby the shield may be swung entirely clear of the bowl mouth. 130

8. A smoking pipe having a shield pivotally attached to the bowl of the pipe, and adapted to cover the mouth thereof, said shield consisting of a disk-like member having a transverse slit or incision, the material of the disk-like member in rear of the said slit or incision being upset to provide a

raised hood terminating at a substantially vertical draft-opening facing in the direction of the stem of the pipe. ¹⁰

Signed at Richmond, in the county of Henrico and State of Virginia, this 4th day of April, A. D. 1921.

JOHN N. DART.
